UNITED STATES PATENT OFFICE

2,513,445

ALL PURPOSE WINDOW

George A. Bremeier, Brooklyn, N. Y.

Application September 5, 1946, Serial No. 694,855

2 Claims. (Cl. 20—52.1)

1

This invention relates to window constructions. An object of this invention is to provide an all-weather window construction embodying spaced sliding panels providing selectively either a storm window, a normal window, or a screened window opening.

Another object of this invention is to provide a window construction having opposed sliding glass panels mounted for horizontal sliding movement and including means for locking the abutting edges of the panels together.

A further object of this invention is to provide in a window construction of this kind opposed screen panels which may be selectively moved to operative position across the window opening, or may be disposed within the wall in inoperative position.

A still further object of this invention is to provide a window assembly which is complete in itself, whereby it may be installed in the walls of a house or other building during the initial construction thereof, or may be fixed onto the walls of completed buildings in registry with the present windows or window openings.

With the above and other objects in view, my invention consists in the arrangement, combination and details of construction disclosed in the drawings and specification, and then more particularly pointed out in the appended claims.

In the drawings:

Figure 1 is a vertical section, partly broken away, of my window assembly.

Figure 2 is a transverse section, partly broken away, taken on the line 2—2 of Figure 1.

Figure 3 is a transverse section, partly broken away, taken on the line 3—3 of Figure 1.

Figure 4 is a fragmentary side elevation, of the latch on my assembly; and

Figure 5 is a transverse section, taken on the line 5—5 of Figure 4.

Referring to the drawings, the numeral 10 designates generally a window assembly constructed according to an embodiment of my invention. The window assembly 10 comprises a pair of laterally spaced apart housings connected together by an upper and lower base rail member, in such a manner that the oppositely disposed housings are adapted to be encased between the inner and outer walls of a building adjacent a window opening. Glass panels, and others, are slidable in the base rail members and are adapted to be enclosed within the housings in their open position, and each panel is adapted to extend halfway across the window opening in the closed position.

2

The window assembly of my invention is adapted to be installed in a building during its construction, or it may be fastened to a building after completion by supporting the assembly inside or outside of the wall thereof with the opposed housings adjacent the window opening. This assembly is equally adaptable to straight or arcuate windows, and may be adapted to a sliding door construction having the rails so positioned that their upper edge does not extend above the door sill.

The housings 11, one at each end of the assembly 10, consist of a rectangular frame having a vertical outer frame member 12 and a pair of laterally spaced apart side walls 14, the outer ends of which abut the inner side of the end member 12 and are fastened thereto. The side walls 14 may be made of wood or asbestos board or other suitable insulating material. The vertical inner edges of the side walls 14 are adapted to be aligned with the sides of the window openings of a building and are covered with a vertical metal channel 15 which provides a wear-resistant edge for the housings 11. The entire housing 11 is adapted to be encased between the inner and outer walls of a building and suitable inner and outer wall material may be secured to the side walls 14 of the housing 11. Suitable finishing edges, as 16, are fixed to the edge reinforcing material or channel 15, which is adapted to extend over the edge of the building walls (not shown), adjacent the housing 11.

A pair of oppositely disposed housings 11 are used for each window assembly 10, and are connected together by an upper base rail member 17, and a lower base rail member 18, which extend into each housing 11 between the side walls 14 and abut the inside surface of the vertical end members or walls 12. The base rails 17 and 18 are formed of U-shaped channel members and are so positioned that the flanges or side arms of the upper base rail 17 extend downwardly and those of the lower base rail 18 extend upwardly, whereby a window may be slidably supported therebetween.

In an original installation in an incomplete building, the base rails 17 and 18 are adapted to be secured to the upper window frame member 19 and the sill 20 respectively, whereas in an installation of the assembly 10 on a completed dwelling, the housings 11 may be fixed to the inner or outer walls of the building.

In the construction of such a window assembly, I contemplate the use of several sliding panels, each providing a different kind of window closure,

as a glass panel, a screen, storm window and a bar panel, each independent of the other, whereby any one or combination may be selectively used at one time. For supporting such panels, there is provided a plurality of L-shaped tracks or guides engageable in the base rails 17 and 18.

For slidably supporting an outer panel 21, as a panel having bars to keep intruders from breaking in, in the rails 17 and 18 at the outer edge an L-shaped guide 22 is fixed with the outer side extending vertically adjacent the outer flange of the rail 17 and 18 and the horizontal side thereof overlying the confronting faces of each base rail between the flanges thereof for engaging and slidably supporting the outer edge of the bar panel 21, the panel 21 sliding on the horizontal side of the guide 22. To support the inner side of the bar 21, another L-shaped guide member 24 is secured in the base rails 17 and 18, having its outer vertical side engaging the inner edge of the bar panel 21 so the bar panel 21 may slide between the guide members 22 and 24.

Another L-shaped guide member 25 is fixed in the rails 17 and 18 having its vertical side spaced inwardly from the vertical side of the member 24 to provide a channeled track for a storm window panel 26. The horizontal side of the member 25 overlies the horizontal side of the member 24 and may, if necessary, be shimmed to provide a snug fit for panels by a shim 27 between the adjacent members 24 and 25.

The innermost panel, as a glass window panel 28, is slidably supported in a U-shaped guide or track 29 fixed in the base rails 17 and 18 and spaced slightly inwardly of the vertical side of the member 25 so that a screen 30, having a thin frame 31 may slide between the U-shaped track 29 and the member 25. Bolts or screws 32, or other suitable attaching means, engage through the nested guide sections in such a manner that any one may be removed when a lesser number of panels is used in the assembly.

The sliding panels are arranged in pairs in the guide means, one of each pair slidable into each housing 11. A center stop bar 34 is fixed across the rails 17 and 18 and guides 22, 24, 25, and 29 midway the length thereof for preventing the panels on each side from sliding past the center of the assembly 10.

The abutting edges of the respective pairs of panels 21, 26, 28, and 30 are provided with interengaging means for sealing the panels in their closed position and locking means for fastening the edge abutting panels in the closed position. On the inner edge of the panels on one side of the center bar 34 there is provided an H-shaped channel member 35 having one pair of arms fixed to the vertical edge of the respective panel and the other pair of arms extending inwardly toward the corresponding panel on the other side of the bar 34. The members 35 are formed with a cut-out or notch on their ends whereby the free arms may extend past the center bar 34. The inner edges of the corresponding panels are adapted to engage between the free arms of the member 35 in their closed position for sealing the joint between the corresponding panel sections.

When the various panels are slid into their respective housings, the inner edge of each protrudes slightly from the inner edge of the housing 11 and a handle or tab 36 is fixed on the inner edge of each panel for manually moving the panel to closed position. The handles 36 are placed in vertically offset positions relative to the handle 36 on the adjacent panel whereby any one panel

may be moved without moving any of the others.

It is desirable to lock certain panels, as the glass panels 26 and 28 in their closed position to provide air conditioned or heated rooms, the space between the panels 26 and 28 providing a dead air space or insulation.

In order to lock the respective glass panels 26 and 28 closed, one panel of each pair, having the H-channel is provided with a transverse locking pin 37 inter-connecting the free arms of the channel. The opposite panel, not having an inner edge strip, is formed with a rectangular cut-out portion 38 opening along its inner edge adjacent the pin 37. A solid plate 39 covers the cut-out 38 on the outer side of the panel and an inner U-shaped plate 40 covers the U-shaped edge of the cut-out 38. The plates 39 and 40 are fastened together and to the panel, as 28, on opposite sides thereof by rivets 41 or other suitable fastening means. An L-shaped lever 42 is rockably mounted between the plates 39 and 40 in the cut-out 38 by a pin 44 extending across the cut-out 38 between the plates 39 and 40. The lever 42 is supported with a substantially horizontal arm extending inwardly from between the inner edges of the plates 39 and 40 to engage between the free arms of the member 35 and is formed with a downwardly opening hook 45 which is engageable with the lock pin 37.

The fulcrum 44 of the lever 42 is at a level above the lock pin 37 so the lever 42 is gravitationally urged to locking position at all times and only the upper portion of the vertical arm is exposed in the cut-out 38 through the U-shaped plate 40. The inner edge of the hook 45 is beveled or rounded so that as the panels come together the beveled edge rises on the pin 37 until the hook falls into locking position. To unlock the lever 42 it is necessary only to move the upper portion of the lever 42 outwardly while pressing the panels outwardly and apart, one from the other.

The assembly 10 may, when installed, be sealed around the edges by weather strips 46 and 47 which are fixed to the frame members 19 and 20.

To protect the edges of the glass panels 26 and 28, strips of felt 48, or other suitable soft material may be secured in the members 35 where the glass edge of the panels engage therein. Felt bumpers 49 are fixed to the inner side of the frame members 12 to provide a soft stop for each of the sliding panels in their fully opened position.

Drain holes 50 are provided in the lower outer edge of each of the rails in order that any condensation or other moisture will be free to drain from the assembly to prevent any subsequent rust or other deleterious effects of water in the rails.

By the use of glass panels of this type, whereby in the use of trim around the edge of the glass panels is eliminated, a larger amount of light may pass through the windows when the panels are in their closed positions.

I do not mean to confine myself to the exact details of construction herein disclosed, but claim all variations falling within the purview of the appended claims.

What I claim is:

1. An all weather window construction comprising upper and lower guides, each of said guides including a horizontal U-shaped elongated channel member formed with vertically extending side legs and a connecting bight portion, a plurality of nested angle members, the outermost

of said angle members disposed within said channel member with the vertical leg of said angle member contiguous with one of said side legs and the horizontal leg on said bight portion, the vertical legs of said angle members being spaced apart, a second channel member having vertical side legs disposed within the innermost of said nested angles and contiguous with the other of said side legs, and opposed pairs of transparent panels slidably engaging said vertical spaced apart angle legs and said vertical legs of said second channel.

2. The construction of claim 1 having the lower guide member thereof provided with drain holes through said vertical legs of said angle members adjacent the bottom thereof and

through one of said vertical side legs of said second channel member adjacent the bottom thereof whereby rain water collecting in said guide member may be drained off.

GEORGE A. BREMEIER.
